UNITED STATES PATENT OFFICE.

FRANCIS K. FASSETT, OF DAYTON, OHIO, ASSIGNOR TO MAX H. FISCHER, OF NEW YORK, N. Y.

CLUTCH.

1,118,518.

Specification of Letters Patent.

Patented Nov. 24, 1914.

Application filed March 21, 1910. Serial No. 550,584.

To all whom it may concern:

Be it known that I, FRANCIS K. FASSETT, a citizen of the United States, residing at Dayton, in the county of Montgomery and State of Ohio, have invented a new and useful Improvement in Clutches, of which the following is a specification.

The object of my invention is to produce a clutch, which when placed on a rod, may be easily moved thereon in either direction; that will grip the rod and become immovable in one direction when pressure is applied to a certain part of the clutch, but which, when the pressure is removed from that certain part, is movable in either direction, as before, without any special act being necessary for its release. One of the uses for such a clutch is to prevent a scarf pin being lost or stolen, and this specification

20 and accompanying drawings will be confined to the form best adapted to this use. Among the scarf pin holders now on the market, there are some sufficiently convenient, so far as placing them on the pin

25 is concerned, but in all that I know of, a certain part, usually small and not easy of access with the holder in position, must be manipulated before it can be removed. In my holder this objection is entirely removed,

30 all the parts being confined in a cylindrical casing by which it is handled, either in putting it on or in removing it from a pin.

In the accompanying drawings, Figure 1 is a longitudinal section; Fig. 2 a similar 35 section, with a pin in place; Fig. 3 a transverse section.

Similar letters and numerals refer to similar parts throughout.

Referring to the drawings, the casing A 40 is secured to the large end of the conical frustum B, the other end of the casing having an opening *a* acting as guide for the small end of an operating member C. The large end of member C is guided by the interior of casing A. The member C has a longitudinal bore *c* opening into a conical recess *c*¹, which incloses, to a variable extent, the frustum B. The latter has a bore *b*, in alignment with bore *c*, and also one or 45 more transverse holes *b*¹, communicating therewith. A ball or roller, preferably a ball, is confined in each hole. A slight contraction of holes *b*¹ at their junctions with the bore, prevents the balls falling into the 50 bore, although permitting a large portion

of each ball to protrude into it. A spring D, confined between the end of the casing and the shoulder formed by the enlargement of the member C, tends to press the member C toward the frustum B, thereby 60 causing the converging sides of the recess *c*¹ to engage and press the balls toward the bore *b*. A pin inserted through the bore *c* into *b*, thrusts the balls obstructing its passage, aside, and the resultant pressure of the balls against the inclined sides of recess *c*, supplemented by such rotary movement as may be imparted to them by the passage of the pin, overcomes the resistance of the spring D and moves the member C outwardly. 70

The strength of the spring is made such that while it creates enough friction between the balls and pin to prevent the holder accidentally slipping off of the pin, the friction is not so great as to prevent 75 it being moved in either direction on the pin, provided it is handled by the casing. Before a pin is inserted, the end of the member C is preferably about flush with the end of the casing, but when a pin is in the 80 holder, this end will protrude beyond the casing more or less, according to the diameter of the pin. But even with the largest pin receivable, its protrusion need be but a short distance, compared to the length of 85 the casing. The pin cannot be withdrawn from the holder if resistance is brought to bear against this protruding end, as the balls, being pressed between the pin and sides of the recess, will rotate and roll into 90 the reduced portion of the recess, thereby causing them to grip the pin tightly and prevent its withdrawal. It would perhaps be more correct to say the balls tend to rotate, as their movement is in fact little more 95 than a tendency, although sufficient to cause them to grip the pin as stated. When an attempt is made to pull a pin protected by one of my holders, out of the tie, the protruding member, being forced against the 100 fabric of the tie, actuates the balls as above described. As soon however as the pressure is removed from the member C, the several parts of the holder resume their normal positions, *i. e.*, those occupied before the balls 105 had been made to grip the pin. This is evidenced by the fact that the pin and holder may be separated as easily after the balls have been made to grip the pin as before, if the holder is handled by its casing. 110

My clutch may be used for other purposes than that of protecting a scarf pin, without departing from the principles or essential parts of the construction described.

5 I therefore claim:

1. In a clutch, the combination of a tubular casing, contracted at one end, a closure fixed in the other end thereof, having an inward free standing extension with a longitudinal bore and one or more transverse holes communicating therewith, a gripping device, confined in each hole, a member within the casing and movable longitudinally therein, having a bore in alinement 10 with that of the closure and a recessed end adapted to inclose the free standing extension, the walls of the recess being oblique and adapted to engage and move the gripping devices, and a spring surrounding the 15 said movable member and confined between a shoulder formed thereon and the contracted end of the casing.

2. A scarf pin guard, comprising a body having an insertion opening, and provided 20 at the end of the body opposite the insertion end with an inclined wall flaring outwardly

and with a shoulder extending outwardly from said body, a head having a central aperture to receive a scarf pin and with lateral apertures, friction balls arranged within 30 said lateral apertures and adapted to extend into the central aperture of said head and to bear against said inclined wall of said body, a coiled spring encircling said body and bearing against said shoulder, and 35 a sleeve overlapping and inclosing said spring and provided with a shoulder connected with said head.

3. A scarf pin guard, comprising a body having an insertion aperture at one end, and at the opposite end an interior inclined wall flaring outwardly, a head provided with a sleeve inclosing the adjacent end of said body, and with a gripping device adapted to bear against said inclined wall, and 40 means arranged between said sleeve and body adapted to press said head toward said inclined wall by spring tension.

FRANCIS K. FASSETT.
